UNITED STATES PATENT OFFICE.

LEVI HENRIKSEN, OF HAMPTON, NEBRASKA.

WRENCH.

1,191,967.

Specification of Letters Patent. Patented July 25, 1916.

Application filed October 27, 1911. Serial No. 657,082.

To all whom it may concern:

Be it known that I, LEVI HENRIKSEN, a citizen of the United States, and a resident of Hampton, in the county of Hamlin, 5 ton and State of Nebraska, have invented certain new and useful Improvements in Wrenches, of which the following is a specification, reference being had to the accompanying drawings.

This invention has relation to an improved wrench of that class known as alligator wrenches; and the object of my invention is to provide a wrench of this general character of a simple and inexpensive nature and 10 of a compact and durable construction including a pivotally held gripper head capable of convenient, accurate and secure adjustment in position upon a workpiece.

With these and other objects in view the present invention consists in the combination 20 and arrangement of parts as will be hereinafter more fully described and finally pointed out in the appended claim, it being further understood that changes in the specific structure shown and described may be 25 made within the scope of the claim, without departing from the spirit of the invention.

In the accompanying drawings forming a part of this specification, and in which like numerals of reference indicate similar parts in the several views: Figure 1, shows a top view of a wrench embodying my invention. Fig. 2, shows a transverse sectional view 35 with portions broken away, and Fig. 3, shows a side elevational view with portions broken away.

While the so-called alligator wrenches are convenient and efficient tools, they are objectionable, as ordinarily constructed, in that the gripping teeth which are practically glass hard, chip off at the ends in the use of the wrench. This occurs when the operator neglects to hold the wrench at right angles to the workpiece, so that all the strain comes on one or more teeth at one end, resulting in the teeth breaking. In my invention I overcome this objectionable feature, in that I provide an alligator wrench in which the pivotally held gripping jaw is protected by two guard plates of a softer material, so that in the operation of the tool should the wrench be tilted under force, the guard plate teeth will bend but protect 55 the intermediately held main gripping teeth. The guard plates are further reversibly and

interchangeably held to the main gripper head, so that as the teeth are worn down, the guard plate can be reversed to bring the opposite arm into play to protect the main 60 gripper head teeth.

In carrying out the aim of my invention I employ two counterpart handle members 1, 1', each at one end having an enlarged offset head, these heads being marked 2, 2', 65 and clearly shown in Fig. 3. Each head has a bolt aperture, the bolt aperture 3', of the handle 1', as shown in Fig. 3, being threaded, while the bolt opening 3, within the remaining handle section 1, ends in a 70 seat 6'. Near the opposite end each handle member has a pivot opening 4, these openings being arranged to receive the rivet 4', connecting the handle members at one end.

Each handle member has a middle lengthwise running channel 5, from which extends the laterally running access opening 6, as disclosed in Fig. 2. As shown in Fig. 3, when united, the heads of the two handle members are held in parallel spaced relation, so as to snugly receive the gripping head, as used in my device. 75

Slidably held within the access opening 5, is a pin 7, and extending from this pin is an operating stud 8, extending through 85 the access opening as shown in Fig. 2, this stud 8, limiting the backward and forward movement of the pin 7, to the rear of which is positioned a coil spring 9, which normally forces the pin 7, outward. The channel 5, is 90 preferably square in cross section to receive the pin 7, though this pin and the channel may be circular.

The gripping member as used in my invention includes a main circular gripper head made of hardened steel embracing 95 two divergently held jaws 11 and 12, shown in Fig. 2, extending from a circular head 10, having edge entering notches 13, the jaw 12, having serrations or gripping teeth 5', 100 as shown. This head 10, has a bolt aperture 14, and an adjacent pin opening 15, and employed in connection with this main gripping head are two similar gripping head guard plates, marked 19, 19', in the drawings, these guard plates being made of a material softer than the main gripper head and in outline conforming to the shape of said main gripping head. As shown in Fig. 1, where one of the counterpart guard plates 110 19, is shown, each includes a circular base 19', from which extend the divergently held 105 25, from which extend the divergently held

jaws 26, 26', these jaws having the teeth serrations 20. Each guard plate is provided with a bolt aperture 27, and a pin aperture 28, registering with the bolt aperture and 5 pin opening within the main gripper head. As shown in Fig. 2, the main jaw member 11, is not provided with any serrations, the inner face *a*, being smooth.

In assembling the wrench, the gripper 10 head is held between two guard plates, as shown in Fig. 3, the guard plates being slightly attenuated, the base portions 25, being of a thickness less than the jaw portions 26, 26'. The guard plates are held to 15 the main head by means of the pin 17, which is removably held within the pin openings. The spring 9, and the pin 7, are then inserted within the channel when the gripping head is carried between the offset 20 heads 2, 2', and secured in position by means of the bolt 16, the head of which is held within the seat 6', the lower end of the bolt 16, threading into the opening 3', as shown in Fig. 3.

25 As shown in Fig. 1, the serrations of the guard plate jaws opposite the main serrated jaw 12, do not come into play as the points of the teeth do not project beyond the inner face *a*, of the jaw 11, the smooth jaw face 30 extending outward to the point of the teeth upon the guard plates upon one side, as shown in Fig. 1. The serrations upon the opposite side, however, exactly register with the serrations of the gripping jaw 12, as 35 shown in Fig. 3. The gripping member of my wrench can be turned at any angle, in simply drawing the pin 7, rearward, properly adjusting the jaw head, and allowing the pin 7, to find a proper seat between two 40 teeth 13. In this position the teeth serrations upon one side may be brought into firm engagement with the work-piece. Now should the operator tilt the wrench so that

all of the strain will be brought against the end of one or two teeth, these teeth will 45 be bent and would be mutilated as they are made of softer material, while the hard interposed gripping teeth 5', will be saved and protected. As the soft teeth upon the active jaw of the guard plates wear out, they 50 are reversed, so that the mutilated teeth are carried upon the smooth jaw 11, the new soft edged teeth being brought into alinement with the main hardened gripping teeth 5'. 55

It is of course understood that these wrenches may be made in several sizes. The tool is simple and inexpensive in construction and both durable and efficient in operation, and the guard plates can be reversed with ease and accuracy. The pin 17, has 60 been described as loosely held within the pin openings, this pin being prevented from becoming displaced in that the same is slidably held against the inner faces of the handle heads 2, 2'. 65

Having thus described my said invention, what I claim as new and desire to secure by United States Letters Patent is:

A wrench including a main head having two divergently held jaws one of said jaws 70 having its face cut into gripping teeth the other jaw having a smooth active face, said gripping teeth being hardened, two guard plates of material softer than said head in outline conforming to the shape of said head 75 located upon opposite sides of said head said soft plates having teeth guarding the hardened teeth of said wrench head, and means to hold said soft plates to said main head.

In testimony whereof I affix my signature, 80 in presence of two witnesses.

LEVI HENRIKSEN.
